US0D1098643S

(12) **United States Design Patent** (10) Patent No.: **US D1,098,643 S**
(45) Date of Patent: ** Oct. 14, 2025

(54) **MAIN BODY FOR ELECTRIC CLEANING APPLIANCE**

(71) Applicant: **Dreame Innovation Technology (Suzhou) Co., Ltd.**, Suzhou (CN)

(72) Inventors: **Mingpu Ren**, Jiangsu (CN); **Nan Jiang**, Jiangsu (CN)

(73) Assignee: **Dreame Innovation Technology (Suzhou) Co., Ltd.**, Suzhou (CN)

(**) Term: **15 Years**

(21) Appl. No.: **35/518,932**

(22) Filed: **Nov. 8, 2022**

(80) **Hague Agreement Data**

Int. Filing Date: **Nov. 8, 2022**

Int. Reg. No.: **DM/227271**

Int. Reg. Date: **Nov. 8, 2022**

Int. Reg. Pub. Date: **Nov. 10, 2023**

(30) **Foreign Application Priority Data**

May 9, 2022 (CN) 202230269768.4

(51) LOC (15) Cl. **15-05**

(52) U.S. Cl.

USPC **D32/22**

(58) **Field of Classification Search**

USPC D32/21-24, 32-33; D4/116, 121

CPC A47L 9/1641; B04C 9/00

(57) **CLAIM**

The ornamental design for a main body for electric cleaning appliance as shown and described.

DESCRIPTION

1. Main body for electric cleaning appliance

1.1: Front

1.2: Back

1.3: Left

1.4: Right

1.5: Top

1.6: Bottom

1.7: Perspective

New designs related to main bodies for electric cleaning appliances which are used as components of the appliances for floor cleaning or washing; the designs characteristics lie in the shape and the reproduction best showing thereof is the perspective view 1.7; the dotted/dashed lines of the designs are for illustrative purposes only and form no part of the claimed designs.

1 Claim, 7 Drawing Sheets
